Shockdoctor Power Dry System; www.shockdoctor.com/products/technology/power-dry-trade.aspx; Jan. 14, 2009.*Primary Examiner*—Elizabeth A Albert*Assistant Examiner*—Kelley A Donnelly(74) *Attorney, Agent, or Firm*—Patterson, Thuente, Skaar & Christensen, P.A.(57) **CLAIM**

We claim the ornamental design for a team room locker, as shown and described.

DESCRIPTION

FIG. 1 is a front perspective view of a team room locker according to the present invention;

FIG. 2 is a front elevational view thereof;

FIG. 3 is a right side elevational view, the opposite side being a mirror image thereof; and,

FIG. 4 is a top plan view thereof.

The broken lines represent environmental elements only and form no part of the claimed design.
